(57) **CLAIM**

The ornamental design for a luminaire, as shown and described.

DESCRIPTION

FIG. 1 is a perspective view of a luminaire showing our design;

FIG. 2 is another perspective view thereof;

FIG. 3 is a left side elevational view thereof;

FIG. 4 is a right side elevational view thereof;

FIG. 5 is a front elevational view thereof; and,

FIG. 6 is a top plan view thereof.

The back of the luminaire is unornamented and not visible in normal use, since it is mounted against a wall or other structural member. Therefore, the back of the luminaire forms no part of the claimed design, and the rear elevational view has been omitted.
